UNITED STATES PATENT OFFICE.

ALBERT P. HAUSER AND OTTO J. HAUSER, OF CLEVELAND, OHIO.

BLADE-HANDLING TOOL.

Application filed February 15, 1923. Serial No. 619,197.

To all whom it may concern:

Be it known that we, ALBERT P. HAUSER, and OTTO J. HAUSER, citizens of the United States, residing at Cleveland, in the county of Cuyahoga and State of Ohio, have invented certain new and useful Improvements in Blade-Handling Tools, of which the following is a specification.

This invention relates to improvements in blade holding tools, the present embodiment of the invention being particularly designed and adapted for use in holding and using safety razor blades of varying forms and types. The present tool is of particular utility in the hands of sign painters in removing the painted matter of letters or signs from the surfaces of glass, and the like.

The primary object of the invention is to provide a generally improved blade holding tool of the class or type indicated which will be exceedingly simple in construction, cheap of manufacture, and efficient in use.

A further and very important object is the provision of a blade holding tool where- 25 in the blade being used may not only be held in secured position for use but may be readily removed when desired or for the reversal or removal of the particular blade being used.

30 A still further and important object is the provision of a tool having blade receiving and holding jaws adapted to be opened and closed in the operation of inserting or removing the blade, the jaws in one of the 35 embodiments of the invention being adapted to be operated through the movements of the handle loop members by the hand while resting on the latter.

There are other features of the invention 40 residing in elemental combinations and particular construction of parts, all as will hereinafter more fully appear.

With the above mentioned and other ends in view, the invention consists in the novel 45 construction, arrangement and combination of parts, hereinafter described, illustrated in some of its embodiments in the accompanying drawings and particularly pointed out in the appended claims.

50 Referring to the drawings, forming a part of this specification, Figure 1 is a perspective view of a blade holding tool, constructed in accordance with this invention, in its operative or blade holding position, 55 and equipped with a safety razor blade of the ordinary Gillette type.

Fig. 2, a side elevation, partly in longitudinal section, the base or abutting portion of the jaws being transformed into a fulcrum and the jaws being moved into and held in an open position by the inward pressure or movement of the spring handle loop members toward each other for releasing a new blade.

Fig. 3, a side elevation of a modified form in which, as distinguished from Figs. 1 and 2, the jaws are held in a closed position by a holding and adjusting element and the spring loop members tend to open the jaws.

Fig. 4, a perspective view of a safety razor blade of the bar reinforced or Gem type.

Fig. 5, a top plan view of a blade of the Durham-Duplex type.

Fig. 6, a plan view of a blade of the Gillette type.

Similar numerals of reference designate like parts throughout all the figures of the drawings.

The improved blade holding tool preferably comprises a handle portion and a blade holding head, the latter preferably corresponding approximately in width to the length of the particular blade to be received and held.

The improved holder is preferably made up of a single length of sheet metal bent midway of its ends forming a handle loop made up of spaced loop members 1, terminating in blade receiving and holding jaws 1^a. The jaws terminate at their outer or free ends in parallel extending lip members 1^b, adapted to engage the intermediate portion of an ordinary safety razor blade.

As a means of holding and supporting the blade being held between the jaws 1^a and particularly as a means of preventing relative longitudinal movement or displacement of the blade between the jaws and holding the outer or operative edge of the blade in a relatively fixed distance in front of the lip members 1^b, the jaws are provided at their inner base portions with a blade edge receiving and supporting portion consisting, in the present instance, of blade edge supporting abutments 1^c. In the present instance, the blade edge supporting abutments 1^c are in the specific form of struck-out tongues and since the base portions of the jaws extend parallel or in abutting relation the opposite jaw is provided with correspondingly located recesses or openings 1^d, to receive

and contain the edges of said tongue members 1^a when the jaws are in their closed or blade holding position.

The loop members 1 are preferably formed 5 of outwardly curved spring material and in the form shown in Figs. 1 and 2 of the drawings such handle loop members are placed under such spring tension as to normally close the jaws and hold the latter in 10 the position shown in Fig. 1 of the drawings and with sufficient tension to properly clamp the blade therebetween.

In the form shown in Fig. 3 the spring 15 loop members are normally in an expanded or separated position and are drawn to their closed position and held in such position by means of an adjusting and connecting element, said element, in the present instance, comprising a connecting bolt 2, threaded at 20 one end and extending through a suitable opening in the base portion of the opposite jaw and provided with a knurled thumb nut 2^a, for drawing or adjusting the jaws or for releasing the latter as desired.

25 As a means of adapting the jaws to receive and hold safety razor blades of varying forms or types, and particularly as a means of receiving and holding a single edge blade 3, having a blade edge bar 3^a, as 30 indicated in Fig. 4 of the drawings, the jaws 1^a are provided with transversely extending spaced offset portions 1^b, said offset portions, in the present instance, being in the 35 specific form of transverse recesses or channel portions conforming on their inner sides to the general form or contour of the blade bar 3^a when the blade 3 is inserted with the edge of the latter extending in front of the jaws.

40 As a means of opening or causing the jaws 1^a to be moved apart to receive or discharge a blade, the jaws are extended rearwardly in parallel relation to provide a base or heel portion 1^c at the terminating portion 45 of the inwardly closed spring loop members

so that as the latter are moved toward each other by the pressure of the hand of the operator while resting on said handle loop members, the base or heel portion 1^c will be transformed into a fulcrum to open the 50 jaws, as shown most clearly in Fig. 2 of the drawings. In Figs. 1 and 6 of the drawings the blade 3^b is of the ordinary Gillette type but it will be apparent that if desired a blade 3^c of the Durham-Duplex type, as shown in 55 Fig. 5 of the drawings, may be used.

Having thus described some of the embodiments of this invention, without having attempted to set forth all the forms in which it may be made, or all the modes of its use, 60 what we claim and desire to secure by Letters Patent is,—

1. In a blade holding tool, a one-piece holder comprising outwardly curved and spaced spring loop members terminating at 65 their ends in parallel extending jaws extending laterally approximately the length of the razor blade to be held, one of said jaws being provided with struck-out tongues forming blade edge supporting abutments 70 and the other being provided with recesses to receive said struck-out tongues.

2. In a blade holding tool, a holder comprising outwardly curved and spaced spring loop members terminating in parallel extending jaws extending laterally approximately the length of the razor blade to be held, one of said jaws being provided in its base portion with struck-out tongues forming blade edge supporting abutments and the other 75 being provided with openings receiving said struck-out tongues when said jaws are closed, said jaws being also provided on their inner sides with transverse channel portions to receive a razor blade edge bar. 80

85 In testimony whereof we have affixed our signatures.

ALBERT P. HAUSER.
OTTO J. HAUSER.
